UNITED STATES PATENT OFFICE.

NICHOLAS ENGQUIST, OF PHILADELPHIA, PENNSYLVANIA, ASSIGNOR OF TWO-THIRDS TO EDWARD G. WHITESIDES AND GEORGE C. WHITESIDES, BOTH OF SAME PLACE.

SPIGOT FOR REFRIGERATORS OR WATER-COOLERS.

SPECIFICATION forming part of Letters Patent No. 429,121, dated June 3, 1890.

Application filed October 3, 1889. Serial No. 325,881. (No model.)

To all whom it may concern:

Be it known that I, NICHOLAS ENGQUIST, a subject of the King of Sweden, and a resident of Philadelphia, Pennsylvania, have invented 5 certain Improvements in Spigots for Refrigerators or Water-Coolers, of which the following is a specification.

One object of my invention is to so construct a spigot for refrigerators or water-coolers that 10 the same will be screened from view and will not be liable to be accidentally opened by contact with the dress of a person passing the refrigerator, a further object being to prevent drip and yet dispense with the usual tumbler-holder beneath the spigot. These objects I 15 attain in the manner hereinafter set forth, reference being had to the accompanying drawings, in which—

Figure 1 is a view, partly in section and 20 partly in elevation, of part of a refrigerator or water-cooler with a spigot constructed in accordance with my invention, the parts being in the position assumed when the valve of the spigot is closed. Fig. 2 is a sectional view 25 showing the valve of the spigot opened. Fig. 3 is a further section of the spigot, showing its valve closed; and Fig. 4 is a transverse section on the line 1 2, Fig. 1.

A represents part of the outer casing of a 30 refrigerator or water-cooler, and B part of the water receptacle or tank of the same, into which, near the bottom, is screwed the inner portion of the valve-casing D of the spigot, the latter projecting through an opening in 35 the outer casing A and having an internal seat a for a valve b, which is acted upon by a spring d tending to close it against the seat, the stem of the valve passing through the end of the casing and being provided at its outer end 40 with an enlarged head f.

Free to slide longitudinally on the casing of the spigot is a ring or yoke g, connected by rods h to the head of the valve-stem, and depending from this yoke is a drip-catcher F, 45 having a tube i extending inward through the casing A and terminating above the usual drip catcher or tray G, located beneath the tank B within the casing of the refrigerator. It will thus be seen that as the valve-stem is

moved inward to open the valve the drip-catcher will be carried inward likewise, so as not to interfere with the free discharge of the water from the nozzle m of the spigot, the drip-catcher resuming its position beneath said nozzle as the valve is closed, so as to catch 55 any drip from the nozzle and convey it to the drip-tray within the casing.

The valve b has a forwardly-projecting stem b', which fits snugly to the opening in the valve-seat, and is of such length that as the 60 valve is opened the flow of water through the opening in the valve-seat is prevented until the drip-catcher has been moved away from beneath the nozzle of the spigot, as shown in Fig. 2.

The spigot and its drip-catcher are inclosed 65 within an outer casing H, confined between the casing A and a shoulder on the valve-casing D, the outer portion of this external casing being made in any ornamental form which 70 may be desired, and an opening formed in the bottom of the casing for the discharge of the water from the spigot.

Hung to the external casing is a lever J, having a portion n within the casing and a 75 portion n' outside of the same, the portion n of the lever bearing upon the head f of the valve-stem, so that by drawing forward the depending portion n' of the lever in the direction of the arrow, Fig. 1, the valve-stem 80 will be pushed into the casing of the spigot and the valve will be opened, as shown in Fig. 2, the depending portion of the lever dropping to its normal or vertical position when the valve is closed, as shown in Fig. 1. 85 It may in some cases, however, be advisable to hold the valve open for a considerable time, and for this reason the head f of the valve-stem has a notch w, with which the portion n of the operating-lever engages when the valve 90 is fully opened, as shown in Fig. 2, so as to hold the valve in this position, the valve being released and permitted to close when the lever is thrown down in the direction of the arrow, Fig. 2.

The opposite bars of the operating-lever are 95 preferably bent or recessed, so as to form shoulders w' at the fulcrum-point for engag-

ing with the opposite edges of an opening w' , formed in the bottom of the casing H , the bars being pressed together to permit of their introduction into the casing, and then allowed 5 to spring apart when the shoulders are in position to engage with the casing.

- As the spigot is entirely inclosed, it is not likely that there will be any accidental opening of the same, such as, in the case of an ordinary spigot, is sometimes caused by contact of the spigot-handle with the dress of a passing person, and as the outer casing may be made of a highly-ornamental character and the necessity for providing beneath the spigot 10 a tumbler-holder or equivalent drip-catcher is wholly obviated my improved spigot is especially applicable to ornamental sideboard-refrigerators, where excrescences of this sort are objectionable.
- Having thus described my invention, I claim and desire to secure by Letters Patent—
1. The combination of a refrigerator or like structure and its spigot-easing, with projecting valve-stem and outer casing inclosing said 15 spigot, and a lever hung to said outer casing and having within the same an arm for acting upon the projecting valve-stem of the spigot, substantially as specified.
  2. The combination of a refrigerator or like 20 structure having a spigot with longitudinally-sliding valve-stem and a sliding drip-catcher

movable with said valve-stem, substantially as specified.

3. The combination of the refrigerator or like structure and its spigot, having a projecting valve-stem with notched head, the outer casing inclosing the spigot, and an operating-lever hung to said outer casing and having within the same a portion for acting on the valve-stem and engaging with the 35 notched head of the same to hold the valve in the open position, substantially as specified.

4. The combination of the spigot and its longitudinally-moving valve, the drip-catcher moving with said valve, and a projecting stem 40 on the valve for closing the spigot-opening until the drip-catcher has been moved from beneath the nozzle, substantially as specified.

5. The combination of the spigot and its valve-stem, the inclosing-casing having an 45 opening therein, and the operating-lever for the valve passing through said opening and having opposite bars recessed for engagement with the casing, substantially as specified.

In testimony whereof I have signed my 50 name to this specification in the presence of two subscribing witnesses.

NICHOLAS ENGQUIST.
